UNITED STATES PATENT OFFICE.

GEORGE M. TEPFER, OF NEW YORK, N. Y., ASSIGNOR TO NATIONAL METAL SPINNING & STAMPING COMPANY, OF NEW YORK, N. Y., A CORPORATION OF NEW YORK.

DESIGN FOR A SHELL FOR LIGHTING-FIXTURES.

48,534.

Specification for Design.

Patented Feb. 8, 1916.

Application filed November 27, 1915. Serial No. 63,900. Term of patent 7 years.

To all whom it may concern:

Be it known that I, GEORGE M. TEPFER, a citizen of the United States, residing at New York city, in the county and State of New York, have invented a new, original, and ornamental Design for a Shell for Lighting-Fixtures, of which the following is a specification, reference being had to the accompanying drawing, forming part thereof.

The figure is a perspective view of a shell for lighting fixtures showing my new design.

I claim:—

The ornamental design for a shell for lighting fixtures, as shown.

GEORGE M. TEPFER.
